DESIGN FOR A DISPLAY BOX

Eugene Lux, New York, N. Y., assignor to Bulova
Watch Company, Incorporated, New York,
N. Y., a corporation of New York

Application February 21, 1941, Serial No. 99,160

Term of patent 7 years

To all whom it may concern:

Be it known that I, Eugene Lux, a citizen of the United States, residing in New York city, county and State of New York, have invented a new, original, and ornamental Design for a Display Box, of which the following is a specification, reference being had to the accompanying drawing, forming part thereof.

Figure 1 is a view in perspective as viewed from the front of a display box, showing my new design;

Figure 2 is a view in perspective thereof as viewed from the rear; and

Figure 3 is a perspective view thereof, as viewed from the front, showing the box as it appears when the cover is raised.

I claim:

The ornamental design for a display box, substantially as shown.

EUGENE LUX.
